UNITED STATES PATENT OFFICE.

HENRY C. MILLER, OF WATERFORD, NEW YORK.

MACHINE FOR LOCATING BUTTONHOLES IN COLLARS.

SPECIFICATION forming part of Letters Patent No. 793,008, dated June 20, 1905.

Application filed September 24, 1903. Serial No. 174,481.

To all whom it may concern:

Be it known that I, HENRY C. MILLER, a citizen of the United States, residing at Waterford, in the county of Saratoga and State 5 of New York, have invented new and useful Improvements in Machines for Locating Buttonholes in Collars, of which the following is a specification.

This invention relates to a machine for locating central buttonholes in collars.

The object of the invention is to provide a machine for accurately forming and locating the center buttonhole exactly midway between the ends of a collar.

15 A further object of the invention is to provide means for quickly engaging and holding the collar ends prior to the operation of the buttonhole-forming mechanism.

Another object of the invention is to provide 20 means for successively opening the end-gages and moving the latter toward each other to receive a collar which is to be operated upon.

Other objects and advantages will be hereinafter referred to and be particularly pointed out in the claims.

In the drawings, Figure 1 is a plan view of a machine embodying my improvements. Fig. 2 is a front elevation of the same. Fig. 3 is an enlarged detail view of one of the gages and its operating means, the gage being in section. Fig. 4 is a plan view of the same. Fig. 5 is a sectional view on the line 1 1, Fig. 4, the gage-operating means being in full lines. Fig. 6 is an enlarged view in elevation of one of the gages. Fig. 7 is a vertical section taken on the line 2 2, Fig. 6, illustrating a gage for positioning a collar which has no buttonhole-tabs. Fig. 8 is a detail plan view of a guide to engage the end of a collar. Fig. 9 is a detail side view of the same. Fig. 10 is a detail bottom plan view of the same. Fig. 11 is an enlarged detail section on the line 3 3, Fig. 5. Fig. 12 is an enlarged detail view 45 of the gage, partially in section, the holding means being in normal position. Fig. 13 is a similar view showing the end of a collar held by the gage. Fig. 14 is a section on the line 4 4, Fig. 13. Fig. 15 is a view of a modified

form of gage. Fig. 16 is a section showing 50 another modified form of gage.

A represents a bench or support, A' a plate mounted on the support and extending forward of the same, as at a'. The plate is provided with ways a and posts B, the latter 55 supporting the work-table A². A buttonhole-machine C, mounted on a bed B', is carried by plate A' and guided in the ways a.

Shafts B² extend vertically through the posts B and carry at their lower ends arms b, which 60 are connected by a bar K', and to the upper ends of the shafts are secured other crank-arms b'.

The buttonhole-machine may be of any preferred type and comprises a head C, needle-bar c', needle c², blade c³, cloth-clamping plates c⁴, and mechanism for operating the same. However, the parts described do not specifically form any part of this invention, being covered by a copending application filed April 19, 1902, Serial No. 103,741.

D represents a yoke or double crank-shaft mounted in bearings D' on the work-table A². The shaft comprises a central horizontal portion d and crank-arms d' d'', which are connected with gages E E and mechanism to operate the latter. The gages slide in ways F F in the support A and are duplicates. Each gage is mounted on a base F', slideable in the way F, said base having formed in its upper 80 surface a seat h' and a projection extending through the way, which prevents its turning. An arm G is carried by the base, and at its outer end it is provided with a sleeve G', in which operates a movable collar-engaging pin 85 H, pointed at its lower end h to engage the end Z of a collar. The upper end h² of the pin is pivotally connected to one end of a lever G² by a pivot g, working in a slot g', said lever being pivotally connected by a pin g² 90 to arm G. A guide H' is loosely mounted on the pin H below the sleeve G', and it consists of a circular body h², formed with a central opening h³, a downwardly-extending lug or guide proper, h⁴, and a cut-away portion h⁵. A pin H² depends from the sleeve G' adjacent the cut-away portion h⁵ and limits the swiveling movement of the guide on the pin H.

A link I is pivoted to the outer end of the lever G², and the lower end of said link is provided with a loop, which loosely engages the crank d', which permits an operator to raise 5 one of the pins H without lifting the other. A spiral spring I' encircles the link between a collar I³, secured thereon, and a stationary lug I², which normally forces the pin H in its seat. A rod J is threaded in the base F' of 10 one of the gages E, and it is held thereto by a nut j, and encircling the rod is a spring J³, located between a movable stop J' and nut J². The crank-arms are formed at their inner 15 ends with split sleeves K, clamped to the posts B, and are connected at their outer ends to the bar K', so that both gages may be operated simultaneously.

The mechanism for operating the gages is pivoted to a bracket M', depending from the 20 support A, and consists of a bell-crank lever M, pivoted at m' and carrying at its lower end a pin l², on which is pivotally mounted a second bell-crank lever L'. The opposite end m³ of lever M is provided with a pivoted stud 25 m⁴, having an opening and screw n', which engages a rod N, and its opposite end is connected to a lug n on the crank d'. The movement of the lever M is limited by the bracket M' and a projection M⁵, and a spring M³ is 30 connected to a projection M⁴ by a threaded rod m⁵ and nut m⁶ to normally hold the lever against said bracket, as shown in Fig. 3. To the end l of lever L' is pivoted a stud provided with a screw l' to engage a connection L, whose 35 opposite end is pivotally connected to bar K'. A link P³ is secured by a set-screw p', having wings p², to a pivoted lug P⁴ on the arm l³ of lever L', and to the lower end of link P³ is a 40 pedal P, mounted on a pin in standards P' on the floor P². A series of sockets f' are formed in the under side of each base F², into any one of which a pin F² may fit. A roller o is mounted on the pin F², and forks F³ of arms b straddle said roller, and a cotter-pin holds the pin 45 in place.

In operation the operator will first press down the heel end of pedal P, which will actuate the rod L and connecting-rod K' in the direction of arrow 1 in Fig. 3, and through 50 the connections move the gages toward each other, the gages being limited in their movement by the stop J'. A continued pressure on the treadle when the stop J' contacts with the frame will overcome the resistance of 55 spring M³ and rock the crank-lever M and draw down the crank-arm or yoke D, and the cranks d' d' pulling on links I raise the inner ends of arms G² and lift the pins H, the movement of the crank-lever M being limited 60 by the stop M⁵. The gages having been drawn toward each other and the pins H lifted, the operator will now place the edges of the tabs of the collar against the guides (see Figs. 7 and 14) and then releasing pressure on the 65 pedal and spring M³, draws lever M to its nor-

mal position, and through the connections N releases the links I, the springs I' forcing the pins H down, and the ends of the collar are pressed into the seats h'. The operator now transfers pressure to the toe of the pedal, pulling rod P³, which actuates lever L' and moves the bar K', which will simultaneously spread the gages an equidistance from the button-hole-sewing machine, the length of the collar stopping the movement of the gages. Clamping-plate c⁴, previously raised, is now closed 70 on the collar and holds it while the button-hole is formed.

By virtue of the guides being swiveled on the pins H it is not necessary for the operator 80 to carefully level the collar when positioning the ends of the same. The distance between the gages when moved toward each other preparatory to receiving a collar is less than the length of the collar, so that when the operator introduces the ends of the latter under the pins H and against the guides the edges may be slightly angularly disposed. When the gages are spread apart and the collar is drawn 85 taut, the edges bearing against the guides cause 90 the latter to turn to permit of the collar being flattened without ruffling the fabric, which insures the sewing mechanism forming the center buttonhole in the exact predetermined place.

The gages accurately locate the collar with 95 reference to the buttonhole-machine so that when the center buttonhole is formed it will be exactly in the center of the collar, as will be readily understood.

In Fig. 15 I have illustrated a modified form of gage H^x, which is substantially the reverse of the preferred form. The pin H^a is fixed and the coacting element H^b, having a seat, is movable and is operated by an arm H^c, connected to link I by a set-screw h⁸, manipulated in the same manner as hereinbefore described.

In Fig. 16 a fixed pointed lower engaging element h⁹ is located under a movable pin H, which has a seat, the guide coacting with both 100 forms of gages, as shown in Figs. 15 and 16.

Having described my invention, what I claim, and desire to secure by Letters Patent, is—

1. In combination, a buttonhole cutting and stitching machine, movable gage-clamping devices engaging opposite ends of a piece of fabric which is to receive a buttonhole, each movable gage-clamping device comprising a movable element and a coöperating element 115 provided with a seat, means moving the movable element toward the seat, and mechanism for operating the gages to or from each other.

2. In combination, a buttonhole cutting and stitching machine, movable gage-clamping 125 devices engaging a piece of fabric which is to receive a buttonhole, each movable gage comprising a swiveled element, a coöperating element provided with a seat, means moving the movable element toward the seat, and mech- 130

anism for operating the gages to or from each other.

3. In combination, a buttonhole cutting and stitching machine, and a movable gage-clamping device comprising a movable element, a coöperating element provided with a seat, a swiveled guide adjacent the movable element, means moving the movable element toward the seat of the coöperative element, and mechanism for operating the gage.

4. In combination, a buttonhole cutting and stitching machine, two end movable fabric-gaging devices, each fabric-gaging device slidably mounted equidistance from the cutting and stitching mechanism and comprising a movable element, a coöperating seat, and a swiveled guide adjacent the movable element, and mechanism for simultaneously operating the two gaging devices.

5. In combination, a buttonhole cutting and stitching machine, two end movable fabric-gaging devices, each fabric-gaging device slidably mounted equidistance from the cutting and stitching mechanism and comprising a movable element, a coöperating seat, and a swiveled guide adjacent the movable element, means sliding the gages, means operating the movable element toward its seat, and mechanism connected to and operating the gage-sliding means and the means operating the movable element.

6. In combination, a buttonhole cutting and stitching machine, two movable gaging devices engaging the ends of a piece of fabric which is to receive a buttonhole, each gaging device comprising a movable element and a coöperating seat, means for sliding the gaging devices, means operating the movable devices, and mechanism connected to and successively operating the sliding means and the movable element.

7. In combination, a buttonhole cutting and stitching mechanism, two movable gaging devices engaging the ends of a piece of fabric which is to receive a buttonhole, each gaging device comprising a vertically-movable pin, a seat formed to receive the end of said pin, a swiveled guide mounted on the pin, and a means normally spacing the pin from the seat, and mechanism for simultaneously operating the two gaging devices.

8. In combination, a buttonhole-machine consisting essentially of a cutting-blade and a stitching mechanism, two end movable gaging devices, each gaging device comprising a movable member, a seat formed to coöperate with the movable member, a swiveled guide adjacent the movable member, the cutting-blade being in exact center between the two guides at the time of cut of the buttonhole.

9. In combination, a buttonhole cutting and stitching mechanism, two end-gaging devices movable to or from each other, each gaging device comprising a movable element and a seat formed to coöperate with said movable

element, means connected to the movable element to operate it, a yoke having arms with which the said means are connected, mechanism for moving the gaging devices, and mechanism successively operating the yoke and the mechanism which moves the gaging devices.

10. In combination, a buttonhole cutting and stitching mechanism, two end-gaging devices slidably mounted to or from each other, mechanism connecting the two gaging devices, each gaging device comprising a clamp and a guide, a yoke having arms, means loosely connecting the clamps with the arms of the yoke, means for sliding the gaging devices, and means connecting the yoke and the means for sliding the gaging devices, operating means connected to the gage-sliding means, the operation of said means serving to operate the clamps and their connections.

11. In combination, a buttonhole cutting and stitching mechanism, two end-gaging devices mounted to slide to or from each other, each gaging device having means for clamping the end of a collar, a yoke having arms, a connection between the arms and the clamps, said connection fitting the arms loosely, means for operating the yoke, and means for operating the gages to or from each other.

12. In combination, a buttonhole cutting and stitching mechanism, two end-gaging devices each gaging device comprising a movable element, a seat formed to coöperate with the movable element, a swiveled guide mounted on the movable element, and means limiting the movement of the guide, and mechanism operating the movable elements and sliding the gaging devices.

13. In combination, a buttonhole cutting and stitching mechanism, two end-gaging devices, each gaging device comprising a movable element to form a clamp, a guide provided with an opening and loosely mounted on said movable element and adapted to turn thereon, and mechanism for simultaneously operating the movable elements through the openings in the guides to clamp a collar.

14. In combination, a buttonhole cutting and stitching mechanism, two end-gaging devices, each gaging device comprising a movable element, a coöperating seat, a guide formed with an opening and mounted on the movable element, and having a guide-surface and reduced side, and a pin adjacent the reduced side for limiting the movement of the guide, and mechanism for operating the end-gaging devices.

15. In combination, a buttonhole cutting and stitching machine, two movable end-gaging devices adapted to be moved toward or from each other, each end-gaging device comprising, a vertically-movable clamp member a coacting member stationary with relation to the movable member and formed with a recess, a guide supported by the stationary member and formed with an opening through which

the end of the vertically-movable member passes to hold the guide against lateral displacement, and mechanism for operating the gaging devices simultaneously.

5 16. In combination, a buttonhole cutting and stitching machine, two end-gaging devices mounted to slide to or from the buttonhole-machine, each gaging device comprising a slide formed with a recess, a vertically-reciprocating pointed pin mounted with its point in alinement with the recess, and a guide loosely mounted on the pin supported by the slide, and mechanism simultaneously operating the pins toward the recesses for clamping collars adjacent their ends, the edges of the collars bearing against the guides.

10 17. In combination, a buttonhole-machine, a pair of slidably-mounted gaging devices provided with a series of perforations, each slide

15 20 having a pin adapted to fit one of the perforations, a pair of shafts, arms on the shafts which engage the pins of the slides, other arms on the shafts, and means connecting the latter arms to move the slides in opposite directions.

20 25 18. In combination, a buttonhole cutting and stitching machine, a pair of slides carrying gaging devices mounted each an equidistance from the buttonhole cutting and stitching machine, each slide having an arm provided with a sleeve, a pin working in the sleeve, a pivoted lever connected at one end to the pin, a rod connected to the other end of the lever, and a spring on the rod normally forcing the pin toward a seat formed on the slide, a yoke 30 having arms, the rods loosely connected to the arms of the yoke, and means operating the slides and the yoke.

25 30 19. In combination, a buttonhole cutting and stitching machine, a pair of slides carrying gaging devices mounted each an equidistance from the buttonhole cutting and stitching machine, said slide having an arm provided with a sleeve, a pin working in the sleeve, a guide loosely mounted on the pin below the

35 40 sleeve, means limiting the movement of the guide, a pivoted lever connected at one end to the pin, a rod connected to the other end of the lever, and a spring on the rod normally forcing the pin toward a seat formed on the 45 slide, a yoke having arms, the ends of the rods loosely connected to the arms of the yoke, and means operating the slides and the yoke.

40 45 50 55 20. In combination, a buttonhole cutting and stitching machine, a pair of slides carrying gaging devices mounted each an equidistance from the buttonhole cutting and stitching machine, each slide comprising a device to clamp and gage a collar, and an arm connected to said clamp, a rod connected to the 60 arm, a yoke provided with arms, the ends of the rods loosely engaging the arms of the yoke, and means operating the yoke and the slides, the loose connections with the arms sliding freely thereon when the slides are moved.

5 21. In combination, a buttonhole cutting 65 and stitching machine, a pair of slides carrying gaging devices mounted each an equidistance from the buttonhole cutting and stitching machine, each slide comprising a device to clamp and gage a collar, and an arm connected to said clamp, a rod connected to the arm, a yoke provided with arms, the ends of the rods loosely engaging the arms of the yoke, means operating the yoke and the slides by one 70 operation, the loose connections with the arms 75 sliding over the arms prior to the operation of the yoke.

22. In combination, a buttonhole cutting and stitching machine, a pair of slides carrying gaging devices, mechanism for operating 80 the slides toward or from each other, and an adjustable stopping device for limiting the movement of the guides toward each other.

23. In combination, a buttonhole cutting and stitching machine, a pair of slides carrying gaging devices mechanism for operating 85 the slides to or from each other, and an adjustable stopping device provided with a spring-buffer for limiting the movement of the guides toward each other.

24. In combination, a buttonhole cutting and stitching machine, a frame, a pair of slides operating in the frame and carrying gaging devices, mechanism for operating the slides to or from each other, and an adjustable stopping device provided with a spring-buffer carried by one of the slides and operating against the frame for limiting the movement of the slides toward each other.

25. In combination, a buttonhole cutting 100 and stitching machine, a pair of slides mounted to slide equidistance to or from the button-hole cutting and stitching machine, a gaging device carried by each slide, mechanism connecting the slides, mechanism connecting the 105 gaging devices, and mechanism operated to successively operate the slides and then the gaging devices.

26. In combination, a buttonhole cutting and stitching machine, a pair of slides mounted to slide an equidistance to or from the buttonhole cutting and stitching machine, a gaging device carried by each slide, a pair of crank-arms pivotally connected together, one of said arms being pivotally supported, a connection between one of the crank-arms and the clamping devices, a connection between the other crank-arm and the slides, and means for moving the crank-arms to successively operate the slides and then the gaging devices.

27. In combination, a buttonhole cutting and stitching machine, a pair of slides mounted to slide equidistance to or from the button-hole cutting and stitching machine, a gaging device carried by each slide, a pair of crank-arms pivotally connected together, one of said crank-arms being pivotally supported, means connecting one of the crank-arms with the

gaging devices, means connecting the other crank-arm with the slides, means for operating one crank-arm a predetermined distance to move the slides toward each other and by 5 a continued pull effect the movement of the other crank-arm to operate the gages, and means for returning the gages and slides to normal position.

28. In combination, a buttonhole cutting 10 and stitching machine, a pair of slides adapted to move to or from the buttonhole cutting and stitching machine, each slide carrying a gaging device, a yoke having arms, loose connections between the arms and the gaging devices, 15 springs closing the gages, a pair of crank-arms pivoted together, one of the crank-arms being pivotally supported and connected to the yoke, an operating means connected to the other crank-arm, mechanism connecting the 20 pair of slides, and a spring holding the crank-arms in normal position relative to each other.

29. In combination, a buttonhole cutting and stitching machine, a pair of slides adapted to move an equidistance to or from the button- 25 hole cutting and stitching machine, a gaging device carried by each slide and consisting of a clamp and a swiveled guide to clamp and hold an article to receive a buttonhole while the edge of the article bears against the guide 30 and mechanism for operating the slides and the gaging devices.

30. In combination, a buttonhole cutting and stitching machine, a pair of slides adapted to move an equidistance to or from the button- 35 hole cutting and stitching machine, a gaging device carried by each slide and consisting of a clamp and a swiveled guide to clamp and hold an article to receive a buttonhole while the edge of the article bears against the guide, 40 and a second gage to engage the edge of a collar, and mechanism for operating the slides and the gaging devices.

31. In combination, a buttonhole cutting and stitching machine, two gages adapted to 45 be moved equidistance to or from the button-hole cutting and stitching machine, mechanism for simultaneously operating the two gages, and means for independently adjusting the gages.

50 32. In combination, a buttonhole cutting and stitching machine, two slides mounted to slide an equidistance to or from the button-hole cutting and stitching machine, a gaging device carried by each slide, mechanism for 55 simultaneously operating the gages said mechanism also permitting of either of the gages being operated independent of the other.

33. In combination, a buttonhole cutting and stitching machine, and a gage comprising 60 an arm, a movable pin having its free end pivoted to the arm, a coacting element provided with a seat in alinement with the pin, a guide formed with an opening and having a guiding- surface distanced from the center of the pin,

and mechanism for operating the gage inde- 65 pendent of the guide.

34. In combination, a buttonhole cutting and stitching machine, and a gage comprising a pin, a coöperating element provided with a seat opposite the pin, and a swiveled guide 70 loosely mounted to turn centrally of the pin, said guide having a guiding-surface distanced from the pin, and mechanism for operating the pin independent of the guide.

35. In combination, a buttonhole cutting 75 and stitching machine, two slides adapted to slide an equidistance to or from the button-hole cutting and stitching machine, a gaging device carried by each slide, each device comprising a clamping device and a guide, mech- 80 anism connecting the gaging devices, and mechanism for simultaneously operating the clamping devices.

36. In combination, a buttonhole cutting 85 and stitching machine, a gage comprising an arm, a movable pin having its end pivoted to the arm, a coacting member provided with a seat in alinement with the pin, a guide provided with an opening and a guiding-surface distanced from the center of the pin, said 90 guide being mounted to turn centrally on the pin, and mechanism for operating the pin through the opening in the guide.

37. In combination, a buttonhole-stitching 95 machine, a gage comprising a movable ele- ment, a coöperative element provided with a seat in alinement with the movable element, means operating the movable element, a swiv- 100 eled element having a guide adjacent the pin, and means limiting the axial movement of the guide.

38. In combination, a buttonhole cutting and stitching machine, a gage comprising an arm, a movable pin having its end pivoted to the arm, a coacting element provided with a 105 seat in alinement with the pin, a swiveled guide mounted to turn centrally of the pin, said guide having a guiding-surface distanced from the center of the pin, and mechanism for operating the pin independent of the guide. 110

39. In combination a buttonhole-stitching 115 machine, a gage comprising a movable pin, a coöperating member provided with a seat in alinement with the pin, means for operating the pin, and a swiveled element having a guide adjacent the pin.

40. In combination, a buttonhole cutting and stitching mechanism, two end-gaging de- 120 vices slidably mounted, clamping devices carried by the gaging devices, and mechanism for successively sliding the gages and operating the clamping devices.

41. In combination, a buttonhole cutting and stitching mechanism, end-gaging devices, 125 slidably-mounted clamping devices carried by the gaging devices, and mechanism sliding the gaging devices in opposite directions, said mechanisms opening the clamping devices

when the gages are moved toward each other, and closing said clamping devices before said gages are moved away from each other.

42. In combination, a buttonhole-machine, 5 a slide, a movable element mounted on and operable toward the slide, a swiveled element having a guide adjacent the movable element, means for moving the movable element to-

ward the slide to engage a collar, and means for moving the slide toward or from the buttonhole-machine.
